UNITED STATES PATENT OFFICE.

EMIL GATHMANN, OF BALTIMORE, MARYLAND.

SINK-HEAD FOR MOLDS.

1,192,617.

Specification of Letters Patent. Patented July 25, 1916.

Application filed September 19, 1913. Serial No. 790,597.

To all whom it may concern:

Be it known that I, EMIL GATHMANN, a citizen of the United States, residing in Baltimore city, Maryland, have invented 5 certain new and useful Improvements in Sink-Heads for Molds, of which the following is a specification.

This invention relates particularly to molds for casting steel ingots and especially 10 to the sink heads or feeders for such molds, but my improvements may be employed in connection with molds for other kinds of castings.

In several United States Letters Patent 15 heretofore granted to me, I have shown molds for casting steel ingots in which provision is made for conserving the heat of the molten metal at its upper portion and for promoting the cooling of the lower portion 20 of the ingot or casting. I have found that in this class of molds improved results can be obtained beyond that acquired in the usual practice by the use of a feeder or sink head wherein the metal of the casting may 25 be maintained in a molten condition for a suitable period of time at its upper end and thus provide a sufficient supply of liquid metal for feeding the lower portion of the casting to fill the pipe or blow-holes therein 30 until the casting is solid.

In carrying out my invention, I preferably form the main body of the mold in the manner shown in my before-mentioned 35 patents, *i. e.*, with the walls of the lower portion of the mold constructed or equipped to promote the cooling of the ingot or casting; and I also preferably make the walls of the upper portion of the mold somewhat thinner than the walls of the lower portion 40 thereof, causing said walls to gradually decrease in thickness from bottom to top. With a mold thus constructed, I employ a sink head or feeder, constructed to serve not only in feeding the mold but to conserve the 45 heat of the ingot or casting in its upper portion, causing the heat in the upper part of the ingot to pass downwardly in the mold chamber and be conducted in a side-wise direction from the lower part of the ingot or casting through the side walls of the mold. Said sink head or feeder may be of any suitable material, cast iron or steel being preferred, and this casting may be slurred or coated on its inner portion with a wash of 50 fire-clay, graphite or other suitable material designed to resist the direct cutting ac-

tion of the molten metal upon the casting. The feeder has an inner wall inclosing a chamber which receives the molten metal and which contains the upper portion of the 60 casting or ingot, and an outer wall which incloses an annular chamber in which is arranged heat insulating material or a fuel which, when ignited, retards radiation of heat in the upper portion of the metal in 65 the mold and in the feeder head and maintains said metal in a molten condition for the desired period of time. The sink head is preferably made removable so that it may be taken bodily from one mold and placed 70 on another.

When a fuel is employed the feeder is formed with draft openings properly located, and on its base the feeder is provided with a bead or flange to prevent the 75 fluid metal from passing laterally outward between the inner wall or base of the feeder and the top of the mold and thus form horizontal fins which would cause the ingot to hang or stick in the mold, and cause horizontal surface shrinkage cracks in the ingot 80 or casting, also making it difficult to remove the casting from the mold.

In the accompanying drawings: Figure 1 shows a vertical central section through a 85 mold, an ingot and a feeder or sink head embodying my improvements. In this case the diameter of the mold chamber is substantially the same at the top as at the bottom. Fig. 2 is a view similar to Fig. 1, but 90 in this case the mold chamber is larger in diameter at the top than at the bottom. Fig. 3 is a view similar to Figs. 1 and 2, but the mold chamber is larger in diameter at the bottom than at the top. Fig. 1^a is a top 95 plan view of the feeder shown in Fig. 1. Fig. 4 is a detail view, showing a vertical central section through a feeder and a portion of an ingot, the feeder being provided with a coating to prevent the ingot from 100 hanging or sticking to the feeder walls. Fig. 5 is a view similar to Fig. 4, showing how the feeder may be formed in sections and how the ingot may have fuel placed on the top of it with a layer of neutral material 105 between the fuel and the ingot.

The mold proper A in Figs. 1, 2 and 3, is preferably constructed in the manner shown in my previous patents, the walls of the lower portion of the mold *a* being thicker 110 than the walls *a'* at the upper portion of the mold and preferably the thickness of the

- walls gradually decreases from the bottom of the mold to the top thereof. In this way the ingot or casting is gradually cooled from the bottom upwardly. The mold chamber 5 may be of substantially the same diameter from top to bottom, as shown in Fig. 1. It may gradually increase from bottom to top, as shown in Fig. 2, or it may gradually decrease in diameter from bottom to top, as 10 shown in Fig. 3. The mold A may rest upon a stool or support B of any suitable kind. Preferably the mold is formed with lugs α^2 , by means of which it may be lifted and lowered.
- 15 In order to more effectually conserve the heat of the ingot at its upper end and to maintain the metal in a molten condition at the upper portion of the casting, I provide a feeder or sink head C, consisting of an 20 outer wall 1, an inner wall 2, and a base 3. The walls 1 and 2 are spaced to provide an annular chamber 4 for holding suitable fuel or non-conducting material. Draft holes 5 are provided in the base 3 and outer 25 walls 1 to promote combustion when fuel is employed, and links 6 may be employed to which lifting mechanism may be attached for raising and lowering the feeder. The base 3 of the feeder is formed with a rib 30 or flange 7 which projects downwardly into the mold chamber and is designed to prevent the fluid metal from passing laterally outward between the lower wall or base of the feeder and the top of the mold 35 and thus form horizontal fins, which would cause the ingot to hang or stick in the mold and produce horizontal surface cracks and impede the removal of the ingot from the mold.
- 40 Preferably as shown, the chamber e within the wall 2 tapers from its lower end upwardly. In this way, when the ingot or casting freezes it will lower and draw away from the wall 2, producing an air space x which 45 serves as an insulating medium. The annular chamber 4 may be filled with any good non-conducting material, such as plumbago, asbestos, or the like, in which case the draft openings 5 are not used, but preferably the 50 chamber 4 is filled with an inflammable, heat-producing material, such as charcoal, coke, or the like, in which case the draft openings admit air to promote combustion.
- 55 The bottom wall or base of the feeder extends laterally beyond the top of the mold so that draft openings may be made in the base of the feeder, and as before stated, the base of the feeder is made integral with the outer wall of the chamber 4 and preferably 60 also integral with the inner wall thereof so that all parts of the feeder may be removed together and may all be made of metal. In Fig. 5 I have shown a construction in which the inner wall 2 is made separately and this 65 may be made of fire clay or the like, but in

this case the inner wall would be destructible and could generally only be used once.

In practice the inflammable or combustible material is placed in the chamber 4 some time previous to the casting of the ingot so 70 that the walls 2 may be suitably preheated before the molten metal comes into actual contact with them. After the casting is made, more fuel may be added from time to time, and such fuel may also be placed upon 75 the top of the liquid sink head of the casting, as indicated at F in Fig. 5, in which case care should be taken to first cover the upper portion of the casting with a thin layer of neutral material N, such as loam or clay, so 80 that the chemical character of the casting may not be affected.

The sink head can readily be removed from the mold or casting by means of the lifting links 6 after the casting has set and 85 become solidified, and said sink head can then be placed upon an empty mold and be ready for use at any time for additional castings.

In Fig. 4 L indicates a lining or coating 90 of graphite or the like designed to resist the direct cutting action of the molten metal upon the casting.

Instead of making the sink head or feeder with all of its parts integral, I may form the 95 inner wall 2 separately. In this case the wall 2 may be made, if desired, of fire-clay or other similar material.

The device shown in Fig. 5 is a sink head or feeder for ingot molds. The ring of refractory material marked 2 forms one wall 100 of a combustion chamber while the outer wall marked 1 in Fig. 5 may be made of metal. This wall 1, which is arranged in a general vertical direction but preferably 105 tapering upwardly and outwardly, is joined at its lower end to a plate which forms the bottom of the combustion chamber and supports the ring 2.

The flange 7 shows a means for definitely 110 locating the feeder on the top of the mold and it can be easily determined when placing the feeder on the mold when the flange has fully entered the mold cavity and at this time the chamber in the feeder will coincide 115 or register with the mold cavity. In all cases shown the flange is formed integral with the bottom plate of the feeder and is therefore integral with the metallic outer wall thereof. In the first four figures of the 120 drawings the inner wall of the feeder is shown as being formed integral with the bottom plate but said inner wall may be of refractory material as indicated in Fig. 5.

I claim as my invention:

1. The combination with a mold of a sink head or feeder having a chamber to receive the fluid metal and to contain the upper end of the ingot, a flange projecting from its base into the mold chamber to prevent the 125

escape of fluid metal between the base of the feeder and the top of the mold and to thus form fins, and having a chamber to contain material for conserving the heat of the outer 5 end of the ingot, the bottom wall of which feeder supports the heat-conserving material and is removable with the inner and outer walls of the feeder from the mold.

2. The combination with an ingot mold of 10 a removable sink-head or feeder having a chamber to receive fluid metal above the mold cavity and to contain the upper end of the ingot and having an annular chamber to contain material for conserving the heat 5 of the upper end of the ingot, said feeder having inner and outer walls for said annular chamber, and a bottom wall formed integrally with the outer wall which supports the inner wall of the feeder and supports 20 also the heat conserving material, said bottom wall resting on the top of the ingot mold and being removable with the inner and outer walls of the feeder, substantially as described.

25 3. The combination with an ingot mold of a sink-head or feeder having a chamber to receive the fluid metal and to contain the upper end of the ingot, a flange of less internal diameter than the upper end of the 30 mold cavity projecting from the base of the feeder into the mold cavity and covering the joint of the feeder with the top of the mold to prevent fluid metal from escaping laterally from the top of the mold chamber and 35 to thus form a fin, said feeder having a chamber to contain material for conserving the heat of the upper end of the ingot.

4. The combination with an ingot mold of 40 a sink-head or feeder, comprising a bottom wall resting on the top of the mold, and inner and outer walls with a chamber between them for insulating material, and a flange formed integrally with said bottom wall the inner diameter of which is less than 45 the diameter of the mold cavity at its upper end and which flange is of substantially the same external diameter as that of the upper

end of the mold cavity and prevents the lateral escape of fluid metal from said cavity.

5. A feeder for ingot molds, comprising a 50 plate having a central opening and adapted to rest upon the top of a mold, and two concentric walls carried by the plate and forming a combustion chamber, the inner wall being of refractory material. 55

6. A feeder for ingot molds, comprising a plate having a central opening and provided with a marginal wall, and a refractory ring at the opening of the plate and forming with the wall of the plate a combustion chamber. 60

7. A feeder for ingot molds, comprising a plate having a central opening, a marginal wall, and a plurality of openings between the central opening and wall thereof, 65 and a refractory ring carried by the plate at the opening thereof and forming within the wall of said plate a combustion chamber.

8. A feeder for ingot molds, comprising a plate having a central opening, a marginal 70 apertured wall, a plurality of openings between the central opening and the wall, and a refractory ring having its lower end fitting in the central opening of the plate and forming with the wall of said plate a combustion 75 chamber.

9. The combination with an ingot mold of a feeder comprising a metallic bottom plate having a central opening and adapted to rest upon the top of the mold and two concentric walls carried by the plate, the outer 80 wall being integral with said metallic bottom plate, and the inner wall being of refractory material, said feeder being provided with means integral with the outer metallic 85 wall for definitely locating it upon the upper portion of the mold.

In testimony whereof, I have hereunto subscribed my name.

EMIL GATHMANN.
